UNITED STATES PATENT OFFICE.

WILLIAM R. WILSON, OF YONKERS, NEW YORK, ASSIGNOR TO ALBERGER CONDENSER COMPANY, OF NEW YORK, N. Y., A CORPORATION OF NEW YORK.

CENTRIFUGAL, TURBINE, OR SIMILAR PUMP.

1,094,181.

Specification of Letters Patent.

Patented Apr. 21, 1914.

Application filed October 23, 1911. Serial No. 656,279.

To all whom it may concern:

Be it known that I, WILLIAM R. WILSON, a citizen of the United States, residing at Yonkers, in the county of Westchester and 5 State of New York, have invented certain new and useful Improvements in Centrifugal, Turbine, or Similar Pumps, of which the following is a specification, reference being had therein to the accompanying 10 drawing.

My present invention relates to certain new and useful improvements in centrifugal, turbine or similar pumps, and concerns especially the pumping of air and the production 15 of a vacuum.

The invention consists essentially of a rotary impeller of a centrifugal or turbine pump in combination with an inlet for air, gas or vapor, and an inlet for water or other 20 liquid, all arranged so that the channels between the vanes or blades of the impeller will each receive air and water alternately, so that in each of said channels there will be a succession of air pistons and water pistons, so to speak, which will be driven by 25 centrifugal force outwardly into the casing of the pump, the discharge being made to the atmosphere through the discharge of the pump, against atmospheric or higher pressure. 30

The invention also comprises means whereby the water is acted upon by centrifugal force before it is projected into the channels between the blades of the impellers, 35 so that the invention includes means for giving the water a centrifugal flow, which is interrupted so that the jets thereof, as they enter the spaces between the blades of the impeller, are broken and are not continuous, 40 there being furnished in this way an opportunity for the air to enter between the broken portions of the jet; and, as soon as the air is carried into the impeller it, as well as the water, is acted upon centrifugally, 45 and the mixture is discharged into the casing of the pump against atmospheric or higher pressure.

The invention also comprises numerous details and peculiarities in the construction, 50 arrangement and combination of the various parts, substantially as will be hereinafter described and claimed.

In the accompanying drawing illustrating 55 my invention, Figure 1 is a cross-section of my improved centrifugal, turbine or similar pump. Fig. 2 is a longitudinal section of

the same taken at right angles to the section of Fig. 1. Fig. 3 is a section similar to that of Fig. 2, on a diminished scale, of a modified form of the nozzles that deliver 60 the water to the channels of the impeller.

Similar characters of reference designate corresponding parts throughout the different figures of the drawing.

1 designates the casing of a centrifugal 65 pump, which is of the usual form, and is provided with a discharge opening 2 to the atmosphere, through which the mixture of air and water from the impeller finds exit against atmospheric or higher pressure. In 70 the casing 1 is an impeller 3 of the closed type, having vanes or blades 4, which are arranged in a series, as seen in Fig. 2, so that there may be channels or passages 5 between every pair of consecutive vanes. Said vanes 75 or blades 4 in the particular example indicated in the drawing, are shown as providing a sort of a double conical channel. It must be understood, however, that I am not restricted to a channel of this form, for the 80 vanes or blades can be shaped or arranged in any desired manner. The impeller 3 is mounted on a shaft 6 supported in a bearing 7 on the side of the casing 1. This shaft is driven by means of some outside 85 power (not shown).

10 designates a water supply pipe leading from any suitable source. Its inner end, which is inside of the body of the impeller 3, is closed and is provided with a series of 90 openings 11 arranged around said end for the purpose of intermittently supplying water to an encircling series of nozzles 12, of which there may be any number. These nozzles 12 are simply short conical, tubular 95 parts, and are carried by the impeller 3, being preferably cast integral therewith, although they may be attached thereto in any desired manner. Obviously, when firmly attached to the impeller they rotate therewith. They 100 are so arranged as to be directly opposite to the inner ends or mouths of the impeller channels 5 and, hence, are situated so as to project their water, which is received into them, from the pipe 10, through the openings 11, into the impeller channels 5. Between the ends of the nozzles 12 and the channels 5 there is an intervening space 105 of greater or less size, which exists within or communicates with an air chamber 8 having 110 an inlet 9, through which air is admitted into chamber 8 from a condenser or any

other receptacle from which it may be desired to exhaust air.

In Fig. 2 the openings 11 in the pipe 10 are so arranged that three nozzles 12 at a time are shut off from their supply of water, while three nozzles are also being given their supply of water, there being, in this example of the invention, six of the nozzles 12 and only three of the outlet ports 11.

10 In Fig. 3 instead of having six nozzles 12 I have indicated eight nozzles 13, which are the same in structure and arrangement as the nozzles 12; but here in the pipe 10 I have shown two openings 14, which are 15 larger than the openings 11, and each opening 14 is in communication with two contiguous nozzles 13. This arrangement of having two nozzles in communication with a single water port 14 prevents stoppage in 20 the flow of water and insures a quiet operation and a continuous flow through the inlet pipe 10.

By the arrangement which I have just described it will be seen that the water, after 25 being delivered from the water supply pipe 10 to the series of rotating nozzles, is given by the latter nozzles a centrifugal movement before it is projected into the channels 5 of the impeller. There is a break in the 30 jets of water, therefore, as they pass from the nozzles to the channels 5, this break being caused by the shutting off of the water supply to the nozzles, which occurs whenever a nozzle passes out of communication 35 with one of the water ports in the water supply pipe. This break in the jets that are flowing to the impeller channels affords an opportunity for the air in chamber 8 to enter between the broken portions of the 40 water jet. The consequence is that in each of the channels 5 there is a succession of water pistons and of intermediate volumes of air, the volumes of air alternating with the water pistons and the series passing in a 45 train thrown outwardly by centrifugal force, and being delivered into the casing and out through the discharge opening against atmospheric pressure.

One advantage to be mentioned which this 50 invention has is that the water supply may be under practically no head or pressure and the force necessary is applied to it by that portion of the impeller that carries the nozzles.

55 When the nozzles are carried by the impeller, the pumping by the nozzles and that by the impeller will be of like speed. I do not wish, however, to be restricted to supporting the nozzles on the impeller. The 60 initial centrifugal movement given to the water may be imparted by means entirely separate from and independent of the impeller; in which case there will be virtually a mechanism consisting of two impellers rotated at different speeds, though in some

cases there might be a plurality of impellers running at the same speed. In a case where two impellers are used rotating at different speeds, the same intermittent supply of water would be obtained and the same rupturing of the continuity of the water jets would take place, to permit the commingling of the air so that the mixed air and water would be thrown out centrifugally in the same way. But in this latter example the 70 stationary pipe with its lateral ports could be dispensed with. An identical result, therefore, would be obtained by two separate impellers as that in the construction shown in the drawing.

A feature of my invention is, obviously, the pumping of the water centrifugally before it comes in contact with the air and then the pumping of the air and water together by means of the same impeller; but 75 the broad principle is that of alternate air and water pistons in the radial channels of the impeller.

It is obvious, moreover, that many 80 changes may be made in the embodiment of the present invention without exceeding the scope of the claims, and I reserve the liberty, therefore, of changing the mechanical features in so far as such change may be found desirable and necessary to accomplish the 85 best results in actual practice.

Having thus described my invention, what I claim as new and desire to secure by Letters Patent is:—

1. In a centrifugal, turbine, or similar 100 pump, the combination with an impeller, of means for imparting an initial centrifugal motion to the water before it comes into contact with the air, and means for intermittently supplying volumes or plugs of water to the impeller, and entrapping the air between said volumes or plugs of water.

2. In a centrifugal or like pump, the combination with an impeller having a series of channels, of a water supply, an air suction, 105 means for imparting an initial centrifugal motion to the water before it comes in contact with the air, and means for cutting off the water supply at intervals from the channels of the impeller to permit the air suction to be connected with the channels during those intervals.

3. In a centrifugal, turbine, or similar 115 pump, the combination with an impeller having a series of channels, of means for intermittently supplying plugs or volumes of water to said channels and entrapping air between said volumes or plugs of water, and means for causing the said intermittent supply of water to partake of an initial centrifugal motion before it is brought into contact with the air.

4. In a centrifugal, turbine or similar 120 pump, the combination with an impeller, of means for intermittently supplying vol-

times or plugs of water to said impeller and entrapping air between said volumes or plugs of water, said means imparting an initial centrifugal motion to the water before it comes into contact with the air.

5. In a centrifugal or like pump, the combination with an impeller having a series of channels, of means for intermittently supplying water to said channels and entrapping air between the plugs of water, said means imparting an initial centrifugal motion to the water before the water entraps the air.

10. In a centrifugal or like pump, the combination with an impeller, of an air suction and a water suction, and means for intermittently introducing water into the impeller and entrapping air therewith, said means imparting an initial centrifugal motion to the water before it entraps the air.

15. In a centrifugal or like pump, the combination with an impeller, of an air suction and a water suction, and means for intermittently introducing plugs of water 20 into the impeller together with intermediate volumes of air, said means consisting of a series of rotating nozzles.

25. In a centrifugal or like pump, the combination with an impeller having a series of 30 channels, of means for introducing water to the inner ends of said channels intermittently, said means consisting of a series of rotating nozzles which deliver into the said channels, together with means for permitting air to be drawn into the channels between the introduction of the jets of water.

35. In a centrifugal or like pump, the combination with a rotary impeller having a series of channels, of an air suction and a water supply, and means for intermittently introducing plugs of water to the channels and entrapping air between said plugs, said means consisting of a series of rotary nozzles which deliver water into the channels, 40 air being entrapped by said channels during the intervals when the nozzles temporarily cease to deliver.

45. In a centrifugal or like pump, the

combination with a rotary impeller having a series of channels, of an air suction and a water supply, and means for intermittently introducing plugs of water into the channels and entrapping air between said plugs, said means consisting of a series of rotary nozzles which deliver water into the channels, air being entrapped by said channels during the intervals when the nozzles temporarily cease to deliver, said nozzles being carried by the impeller and rotating at the same speed.

50. In a centrifugal or like pump, the combination with a rotary impeller having a series of channels, of a water inlet having a series of outlets, a series of nozzles revolving around said series of outlets and coming into coincidence therewith, said nozzles projecting the water into the inner ends of the channels intermittently, and means for allowing air to enter the channels of the impeller at the times when the water is not being introduced, whereby each channel is 55 filled with a succession of water plugs and alternate quantities of air.

55. In a centrifugal, turbine or similar pump, the combination with an impeller having a series of channels, and carrying also a series of nozzles arranged to deliver into said channels, there being a space intervening between the nozzles and the channels, an air suction communicating with the inner ends of said channels, and means for supplying water to the nozzles and cutting off the supply at intervals, so that the jets of water which issue from the nozzles may be intermittently broken to permit the air 60 suction to be connected with the channels during those intervals, whereby each channel is filled with a succession of water plugs and air pistons.

65. In testimony whereof I affix my signature in presence of two witnesses.

WILLIAM R. WILSON.
